SHOPPING CART

Melvin H. Best, Pasadena, Calif., assignor to The Cal-Dak Company, San Marino, Calif., a corporation of California

Application January 4, 1956, Serial No. 39,606

Term of patent 14 years

(Cl. D14—3)

FIG. 3.

Fig. 1 is a side elevational view of a shopping cart in a collapsed position, embodying my new design;

Fig. 2 is a front elevational view of the collapsed shopping cart shown in Fig. 1; and

Fig. 3 is a perspective view of the cart in its unfolded position.

I claim:

The ornamental design for a shopping cart, as shown and described.
